UNITED STATES PATENT OFFICE.

ROBERT G. DYSON, OF TROOPER, PENNSYLVANIA, ASSIGNOR TO FRANKLIN AIR COMPRESSOR WORKS, OF NORRISTOWN, PENNSYLVANIA, A CORPORATION OF PENNSYLVANIA.

REGULATOR FOR AIR COMPRESSORS.

Application filed July 8, 1922. Serial No. 573,625.

To all whom it may concern:

Be it known that I, ROBERT G. DYSON, a citizen of the United States, residing in Trooper, Pennsylvania, have invented a 5 Regulator for Air Compressors, of which the following is a specification.

My invention relates to devices for removing the load in air and other compressors when the latter are started to permit rapid pick-up of the compressor to 10 normal running speed.

One object of my invention is to provide a device of this nature which will automatically open the intake valve of the compressor during the compression stroke, and which will leave said valve free for normal action during the intake stroke.

A further object of the invention is to provide an unloading device which will 20 function also to balance the crank shaft of the compressor when the latter is either with or without load.

In the attached drawings:

Figure 1, is a side elevation of a compressor, with the fly wheel removed, equipped with an unloading device made in accordance with my invention;

Fig. 2 is a front elevation partially in section of the compressor;

Fig. 3, is a detached enlargement of essential portions of the unloading mechanism, and

Fig. 4 is a section on the line 4-4, Fig. 3.

With reference to the drawings, 1 indicates the casing of the compressor having at the top a cylinder 2, the latter being provided with a head 3, in which is mounted in the usual manner an intake valve 4. The intake valve 4 normally is held to its seat 5 by means of a spring 6 upon the valve stem 7, the spring being adjusted to permit opening of the valve upon each suction stroke of the piston. The compressor further comprises a crank shaft 8 which extends 40 through one side of the casing 1 and which carries a fly wheel 9.

Fixed to the shaft 8 intermediate the casing and the fly wheel is a collar or hub 10^b having an integral arm 10, said hub in the 50 present instance being secured to the shaft by means of a spline 11. Pivotedly secured at 12^a to the arm 10 at one side of an offset 10^a of said arm 10 is a weighted arm 12 of 55 arcuate formation which has a ring 13 secured thereto at one side as clearly shown

in Figure 2 of the drawing, said ring being in the present instance cast integral with the arm 12 and in a position surrounding the hub 10^b.

As best shown in Figure 3, the pivotal movement of the arm 12 on the arm 10 is limited by a shoulder 14 on the arm 10. A spring 15 is attached in the present instance to a pin 16 at the end of the arm 12 and to a screw 16^a on the hub 10^b. The spring 15 65 tends to retain the arm 12 in the position shown in full lines in Figures 1 and 3 when the shaft 8 is at rest or moving slowly, said spring being so constructed when the shaft 8 is rotated at a high speed, to allow the 70 arm 12 to swing into the dot-and-dash line position shown in said Figure 3.

As will be apparent from the drawings, the arrangement of the aforescribed elements is such that when the compressor is 75 idle the ring 13 assumes a position eccentric to the shaft 8. When, however, the compressor is started, the centrifugal force developing in the rotation of the shaft 8 causes the arm 12 to swing outwardly from 80 the shaft against the force of the spring 15 until the pivoted end of the arm engages the shoulder 14, which latter acts as the limit stop for the outward movement. In this 85 extended position of the arm 12, the arrangement of the members is such that the ring 13 assumes a position concentric with the shaft 8, as clearly shown in broken lines in Fig. 3, which illustrates the positions of the arm 12 and the ring 13 when the compressor is both idle and in operation.

Pivotedly mounted upon a bracket 17 on the head 3 is a lever arm 18, in one end of which arm is adjustably secured a bolt 19 which extends downwardly, as shown in 90 Fig. 2, and abuts the upper end of the valve stem 7 of the valve 4. To the other end of the lever 18 is secured a rod 20 which extends downwardly and has its lower end established in a guide element 21 secured to 100 the casing 1. Carried by the rod 20 and extending into the path of the ring 13 when the latter is eccentric to the shaft 8 is a cam roller 23, which latter is adapted to be engaged by the periphery of the cam 105 ring 13.

As shown in Fig. 3, the arm 10 is so arranged on the shaft 8 that the weight 12 lies substantially opposite the crank 24, which latter is indicated by broken lines, to 110

which crank is attached the connecting rod (not shown), which connects the piston (also not shown) of the compressor with the crank shaft 8, the weight of the unloading elements thus being utilized to assist in balancing the crank shaft 8 by reason of their weight being opposed to the offset crank 24. It will be noted that the counterbalancing force thus obtained, which is least, when the speed of rotation of the shaft 8 is also least, gradually increases with the speed of the shaft by reason of the outward movement of the arm 12, this having the effect of balancing the crank shaft for all speeds of the latter, and as will be described hereinafter, both while the compressor is unloaded and loaded.

The operation of the device is as follows: The compressor being started, the arrangement of the cam ring 13 with respect to the crank 24 is such that at the beginning of each compression stroke the ring engages the roller 23, and by elevating the rod 20 forces the valve 4 from its seat and retains it in an open position until the end of the compression stroke. During the intake stroke of the compressor, the ring disengages the roller 23, the valve 4 being permitted to act normally in admitting air to the cylinder. In this manner, the load is entirely relieved from the piston, since the air drawn into the cylinder during the intake stroke is expelled from the cylinder through the same port by reason of the valve being opened by the ring 13 in the manner described.

It will further be noted that by reason of the aforescribed arrangement, the valve 4 at the start is opened to a much greater extent on the compression stroke than on the intake stroke, the opening of the valve on the latter stroke being the normal one caused by the partial vacuum formed in the cylinder as the piston moves downwardly therein. A decided advantage is in this manner obtained over those devices of a similar nature in which the valve is retained in the open position, both during intake and compression strokes, since it will be apparent that less air is drawn into the cylinder during the intake stroke than would be the case were the valve retained in the wide open position which it is made to assume during the compression stroke. The device does not assist on the intake stroke, but does relieve on the compression stroke. A material increase in the starting efficiency of the compressor is thus realized.

As the speed of the compressor increases, the ring 13 moves as previously described gradually into the concentric position, in which position it does not engage the roller 23, the valve 4 thus being released for normal operation. It will be noted that by reason of the movement of the ring 13 into the concentric position, the valve 4 is opened

to a less and less extent as the ring approaches the concentric position, the load being thus gradually placed upon the compressor.

A further decided advantage in this device is found in the aforescribed balancing of the crank shaft 8 by reason of opposing the weight of the elements of the device to the crank 24. It will be apparent that as the speed of the shaft 8 increases together with the load placed upon the compressor, the torque upon the shaft 8 increases proportionately. This gradually increasing strain upon the crank 24 is to some extent offset by the gradually increasing moment of the weight 12 and the associated parts of the unloading elements by reason of the outward movement of the arm 12 from the shaft. The effect thus obtained is a superior balance in the crank shaft by reason of the natural adjustment of the balancing elements as the speed of the shaft increases.

The aforescribed device is an extremely simple one and applicable to any type of compressor whether employed for the compressing of air or other fluid. The device further is found extremely efficient in operation, there being realized a considerable improvement over devices of a similar nature.

It will be understood that the device is capable of considerable modification with no departure from the essential features of the invention.

I claim:

1. Mechanism for use with a compressor having an operating crank shaft and a valve, comprising an unloading device having a centrifugally operative part movable transversely to the axis and directly opposed to the crank of said shaft for causing a balance for said crank when the compressor is either with or without load, said centrifugally operative part being also effective to cause said valve to open during the starting movements of said crank shaft.

2. Mechanism for use with a compressor having an operating crank shaft and a valve, comprising an unloading device having a centrifugally operative part movable transversely to the axis and directly opposed to the crank of said shaft for causing a balance for said crank when the compressor is either with or without load, said centrifugally operative part being also effective to cause said valve to open intermittently during the starting movements of said crank shaft.

3. In mechanism, the combination with a driven shaft, a valve, an arm having a hub directly secured to the shaft, a centrifugally movable member pivotally connected to said arm and included in a plane passing through said hub transversely of its axis, valve actuating means fixed to said member, and

means operative to hold said valve actuating means in a position for effecting the operation of said valve during slow rotations of said shaft, said member, due to centrifugal movement during faster rotations of said shaft, being operative to move said valve operating means into a position not effecting the operation of the valve.

4. In mechanism, the combination with a driven shaft, a valve, an arm having a hub directly secured to the shaft, a centrifugally movable member pivotally connected to said arm, a ring fixed to said centrifugal member, said member and said ring being included in planes passing through said hub transversely of its axis, and means operative to hold said ring in a position for effecting the operation of said valve during slow rotations of said shaft, said member, due to centrifugal movement during faster rotations of said shaft, being operative to move said ring into a position not effecting the operation of the valve.

5. In mechanism, the combination with a driven shaft, a valve, an arm secured directly to the shaft, a centrifugally operative arm pivoted to and adjacent one side surface of said first arm, a ring secured to said centrifugal arm and located at the opposite side of said first arm whereby the pivoted portion of said first arm is positioned between a part of said centrifugal arm and the plane of said ring, said ring upon slow rotation of said shaft being operative to actuate said valve and upon faster rotation of said shaft being movable into a position due to the action of said centrifugal arm as not to actuate said valve.

6. In mechanism, the combination with a driven shaft, a valve, an arm secured directly to the shaft, a centrifugally operative arm pivoted to and adjacent one side surface of said first arm, a ring secured to said centrifugal arm and located at the opposite side of said first arm whereby the pivoted portion of said first arm is positioned between a part of said centrifugal arm and the plane of said ring, said ring upon slow rotation of said shaft being operative to actuate said valve and upon faster

rotation of said shaft being movable into a position due to the action of said centrifugal arm so as not to actuate said valve, said arm having a shoulder portion for limiting the movement of said centrifugal arm. 55

7. Mechanism for use with a compressor having an operating crank shaft and a valve, consisting of an unloading device for said compressor, said unloading device including an arm with a spline connection 60 with said shaft whereby the position of the arm can be definitely set relatively to the crank of the crank shaft, a pivotally mounted centrifugal arm on said first arm and opposed to the crank of said shaft, and means 65 connected to said centrifugal arm for actuating said valve.

8. Mechanism for use with a compressor having an operating shaft and an intake suction valve, including means centrifugally 70 movable with respect to said shaft and having a portion for actuating said valve, means operative counter to centrifugal movement for holding said portion in a position to open said valve intermittently when 75 said shaft is moving slower than its operating speed and to keep said valve open only during the compression strokes of the compressor when said shaft is moving at said slower speed, said holding means being of 80 such strength as to be overcome by said centrifugal movement when said shaft has reached said operating speed to cause said centrifugally movable means to move into a position not effecting the opening of the 85 valve.

9. Mechanism for use with a compressor having an operating crank shaft and a valve, comprising an unloading device having an arm adapted to be secured directly 90 to said shaft, a centrifugal member movably connected to said arm, and means movable by said centrifugal member transversely to the axis of said shaft to intermittently open said valve upon slow rotations of said shaft 95 and movable into a position not opening said valve during faster rotations of said shaft.

ROBERT G. DYSON.
